UNITED STATES PATENT OFFICE.

WALTER J. KAHL, OF NEW YORK, N. Y.

PRINTING-TELEGRAPH PROJECTING MACHINE.

Application filed February 9, 1920. Serial No. 357,230.

To all whom it may concern:

Be it known that I, WALTER J. KAHL, a citizen of the United States, residing in the city of New York, county of Bronx, State of 5 New York, have invented a certain new and useful Improvement in Printing-Telegraph Projecting Machines, of which the following is a specification.

My invention lies in the novel assemblage 10 and construction of a machine and device for automatically enlarging, displaying and projecting on a sheet the news which is telegraphed and printed by the commonly known "news ticker" and "stock quotation 15 ticker". The printing telegraphs now in use allow but six or eight persons to crowd about the "news ticker" to learn of results in election of public officers, world series baseball contests, sporting news, stock exchange 20 information and matters of intense public interest, more than that number of persons cannot possibly see the printed tape at the same time. I have contrived a machine and device which will automatically 25 enlarge and display the news to hundreds or thousands of people just as it leaves the "news ticker". The machine described herein provides for a back projection to a screen attached to the front portion of the 30 container or encasement. Its utility is very apparent in that the machine can be used in the offices of stock brokers and displayed to an audience of customers in place of the quotation board now in use. It can take the 35 place of hand printed bulletin boards in front of newspaper offices and probably serve a useful accomplishment in clubs and hotels. By arranging the combined elements for a long throw front projection to a screen 40 at a distance from the machine, instead of the short throw back projection herein described, the current news can be displayed to a theatre audience of two thousand people in conjunction with a regular theatrical 45 or moving picture performance. A screen small or large could be placed at the side of the stage and the machine automatically operated by telegraphic impulses for a long throw front projection from the rear of the 50 theatre. In this way it could serve a novel, economical and useful purpose; for example, in the general election of public officers it would eliminate the necessity of having an operator continuously consult the "news 55 ticker," prepare slides, insert and project them in a projecting apparatus only to re-

peat the operation over and over again. My invention allows for the news to be automatically enlarged and projected just as it leaves the printing telegraph.

My invention is an improvement in printing telegraph bearing Patent No. 581,411, granted April 27, 1897, and No. 680,693, granted August 20, 1901, and other or similar telegraph recording instruments, in 60 that the improvement provides for a method and device for automatically preparing and producing a perforated tape to be used for projecting to a screen. The general object of this invention, however, is to provide a 65 machine or device for automatically displaying and enlarging on a screen perforated impressions made on a tape or strip of paper by the type wheels of the printing telegraphs which strip of paper is guided and caused 70 to continuously move into the path of the projection rays of a projecting apparatus or stereopticon. Any number of such machines could be simultaneously operated by 75 one telegraph operator.

My invention also consists in providing 80 perforating points or needles on the type-wheels of the printing telegraph which will pierce holes in the strip of paper of the printing telegraph, and through which holes 85 the projecting rays will pass, the paper obstructing all other light so that only the perforated characters will be flashed upon the screen.

It also consists of a means of guiding the 90 perforated strip of paper before the condensing lens of a projecting apparatus and automatically and continuously displaying the impression upon a screen.

The invention may be contained in a 95 variety of constructions, both front and back projections. For the purpose of showing that a construction embodying the invention is operative I shall illustrate one of such constructions, namely, a back projection 100 with the screen attached to the front portion of the container or encasement, and shall hereinafter fully describe the same.

Figure 1, is a side elevation of printing telegraph, Patent No. 581,411, issued April 105 27th, 1897, showing type-wheels etc., on which machine my invention is an improvement.

Figure 2, is a perspective side view of 110 perforating points or needles on the type-wheels and platens beneath type-wheels covered with felt or fibrous material, to act as a

cushion for the needles or perforating points.

Figure 3, is a perspective view showing a portion of the type-wheel with perforating 5 points or needles forming the characters and letters of the alphabet on the type-wheel.

Figure 4, is an enlarged detailed view of the type-wheels on which the perforating points or needles are attached showing 10 platens beneath covered with felt or fibrous material to act as a cushion for the perforating points or needles, and hammer shifting mechanism.

Figure 5, is a view of one side of the construction showing the container thereof in 15 section and with the printing telegraph omitted.

Figure 6, is a similar view of one side of the construction showing the container thereof in section, and with the printing telegraph 20 placed in a position so as to allow the perforated strip of paper to move in the path of the projecting rays.

Figure 7, is a perspective view of the condensing lens in front of which is attached the two strips of glass between which the 25 perforated tape from the printing telegraph passes.

Figure 8, is a plan view of the construction.

Figure 9, is an end elevation of printing telegraph, Patent No. 680,693, issued August 20th, 1901, showing type-wheel, roller 35 platen, etc., upon which my invention is also an improvement.

Similar letters or numbers of reference indicate corresponding parts throughout the figures of the drawings.

Referring to the old structure of printing telegraph shown in Figure 1, and upon which my invention is an improvement, type-wheel *t* is replaced by type-wheels *w*, portions of which are shown in Figures 2 45 and 3. Perforating points or needles *p* attached to the type-wheels form the various characters and letters of the alphabet and are constructed with points sufficiently sharp so as to easily pierce holes in the strip of 50 paper used on the printing telegraph.

Frame *f* and roller *r* from which the type-wheel on the original machine receives ink can be entirely dispensed with. Platens *y* and *z* are partially covered with strips of 55 felt or fibrous material *e* which serve as a cushion for the needles or perforating points on the type-wheels. The felt is held in place on the platens *y* and *z* by means of two strips of steel *s*, which serve as springs, 60 are riveted or screwed on the platens *y* and *z*, and have prongs on the inner horizontal portion as shown in Figure 4, and which tend to grasp the felt and hold it in place.

The strips of felt may thus be readily 65 placed when they become worn by reason of

being continuously pierced by the perforating points or needles.

The operation of the impression taking parts is as follows: The hammer *h* is normally under either platen *y* or platen *z*, and at each "printing impulse" over the line, is forced against the platen causing the felt on the platen to be driven against the perforating needles of a character or letter on wheels *w*. The strip of paper passing between the type-wheels *w* and platens *y* and *z* become pierced with small holes by perforating points or needles *p*, which holes form the desired character or letter of the alphabet.

1, Figures 5 and 6, is a container, encasement or cover for closing the parts embodying the invention. It is placed on base 2 which supports the elements containing the invention. The base may be supported by 85 legs 3 or in any other suitable way. A projecting tube 4, containing projecting lenses is adjustably supported on an adjustable pedestal 5, which is adjustably supported on a standard 6. The standard 6 is secured to 90 base 2. A condensing lens 7 is also adjustably supported on the pedestal 8 which is in turn secured to the base 2. A Nernst glower 9 or other light giving body is supported in line with the lenses for projecting the per-

forated impressions on the strip of paper as they appear in a position of exposure. The glower and its regulating parts are contained in a tube or cylinder 10. The cylinder is supported on a pedestal 11. Attached 95 to the frame which holds the condensing lens 7 is a metal encasement 12, and to which are attached two lengthy strips of narrow glass 13 and 14. The strips of glass are fastened to the encasement 12 by means of 100 metal strips 15 and 16, and are further held in place by metal strips 17 and 18. The printing telegraph with the improved attachments heretofore described is horizontally fastened to frame 20 by means of 105 screws, which frame is fastened to an adjustable pedestal 21 the latter being adjustably supported on the other end of standard 6. The standard 6 is so constructed that the printing telegraph may be raised to a 110 horizontal position at the side of the condensing lens 7 and on a line even with the strips of glass 13 and 14, a short distance from the ends of glass strips at 22 and 23.

The printing telegraph with the improved 115 attachments heretofore described is so fastened to its supporting frame in a horizontal position as will enable the strip of perforated paper which leaves the printing telegraph to pass directly between strips of 120 glass 13 and 14 and to automatically move into a position of exposure. 24 the glass cover of the printing telegraph (designated as *g* in Figure 1) can be entirely dispensed with or an opening cut in it near the ends 125 130

of glass strips 13 and 14 so as to allow the perforated strip of paper to pass from the printing telegraph to the space between glass strips 13 and 14. A roll of black paper 5 should preferably be used on the printing telegraph in order that all the light may be obstructed as the strip passed into a position of exposure before the projecting rays, except the light which passes through the 10 pin holes forming the characters or words which the type-wheels have perforated in the paper. A screen 25 is made of Irish linen or similar material and is placed against a glass on the front of the container 15 or encasement in line with the projecting lenses and upon which screen the projection is made. Shade 26 can be placed on the outside of the container so that a projection may be made in daylight. In the above de- 20 scribed construction the sides of the container can be hinged to base 2 and held in place by catches at the top of the container so that the light, lenses etc. can be readily adjusted. 25 The construction above described relates to a back projection with the screen attached to the front portion of the container or encasement. If desired a front projection can readily be obtained by dispensing with the 30 screen on the front part of the container and by placing the printing telegraph with the improved attachments on the opposite side of the condensing lens in a reverse position and suitably adjusting the lenses for a long 35 throw.

The invention herein contained may also be readily applied to printing telegraph No. 680,693, issued August 20th, 1901, which prints lines across a page or web and of 40 which a side elevation is shown in Figure 9. Type-wheel *a* is replaced by a wheel similar in construction to that shown in wheel *w* of Figures 2 and 3 and the ink roller *i* can be

entirely dispensed with. In addition there- 45 to the metal roller platen *m* is completely covered or encircled with felt or fibrous material to act as a cushion for the perforating points or needles. Two strips of glass the width of the perforated page can be attached in a vertical position to encasement 50 12, and constructed in a manner similar to that shown in Figures 5, 6 and 7. With these attachments and changes in mechanism, the printing telegraph can be supported in an inverted position above the condensing lens 55 of the projecting apparatus so that the perforated page will fall directly in the path of the projecting rays. As heretofore shown this type of printing telegraph with the im- 60 proved mechanism can also be constructed for either a front or back projection.

As above shown the invention is suscepti- 65 ble of many modifications in the construction thereof for which reason I do not limit this specification and the claim to the pre- cise forms of the invention illustrated in the drawings and hereinbefore described.

What I claim as new and desire to se- 70 cure by Letters Patent is as follows:

The method herein described which con- 75 sists in telegraphically receiving and record- ing subject matter in a manner suitable for projection, continuously passing the record- ed subject matter while receiving to a pro- jecting apparatus, and then in a fixed time relation to the recording, continuously and visibly projecting the subject matter sub- 80 stantially as set forth.

In testimony whereof I have signed my name to this specification, this 6th day of February, 1920, in the presence of two sub- 85 scribing witnesses.

WALTER J. KAHL.
